P.L.C.(57) **CLAIM**I claim the ornamental design for a portable electronic device,
as shown.**DESCRIPTION**FIG. 1 is a front/right-side/top perspective view of a portable
electronic device showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.

The dashed broken lines in the drawings represent portions of
the portable electronic device that form no part of the claimed
design. The dot-dash lines in the drawings illustrate the
bounds of the claim and form no part thereof.**1 Claim, 6 Drawing Sheets**(56)
